B. T. LEVEQUE,
METHOD OF ATTACHING BUTTONS TO FABRIC.
APPLICATION FILED JAN. 29, 1909.

UNITED STATES PATENT OFFICE.

BERNARD T. LEVEQUE, OF BOSTON, MASSACHUSETTS, ASSIGNOR TO THE REECE BUTTON-HOLE MACHINE COMPANY, OF BOSTON, MASSACHUSETTS, A CORPORATION OF MAINE.

METHOD OF ATTACHING BUTTONS TO FABRIC.

No. 918,873.

Specification of Letters Patent.

Patented April 20, 1909.

Application filed January 29, 1909. Serial No. 475,072.

To all whom it may concern:

Be it known that I, BERNARD T. LEVEQUE, a subject of the King of Great Britain, and resident of Boston, county of Suffolk, State 5 of Massachusetts, have invented an Improvement in Methods of Attaching Buttons to Fabric, of which the following description, in connection with the accompanying drawing, is a specification, like numerals on the drawing 10 representing like parts.

This invention has for its object the production of a novel method of attaching an eye-button to a fabric in a strong and durable manner by means of interlocking primary 15 and secondary loops of the same thread, so that individual buttons are firmly secured in place, irrespective of the integrity of the intervening portion of thread between two successive buttons.

20 The novel features of the method will be fully described in the subjoined specification and particularly pointed out in the following claims.

In United States Patent No. 886,826 25 granted to me the 5th day of May, 1908 I have shown and described an apparatus for carrying out the method of attaching buttons hereinafter set forth.

Figure 1 of the drawing is an enlarged view 30 of an eye-button and a portion of the fabric, the latter in section, with a primary loop of thread passed through the fabric and through the eye of the button, the button at this time being supported above the fabric; 35 Fig. 2 is a similar view, showing the fabric as having been advanced after the formation of the primary loop, the button-support also moving the button along, so that the button-eye is clear of the path of the needle, and the 40 primary loop is shown in position to be entered by the needle on its next descent. Fig. 3 is a like view, but showing the button as released from its support after a secondary loop of the thread has been passed through 45 the fabric and through the primary loop.

Fig. 4 is a perspective view, showing the secondary loop spread after it has been cast off from the needle preparatory to placing such loop over the button close to the fabric. Fig. 50 5 is a view similar to Fig. 3, but showing the secondary loop after it has been placed over the button and between it and the fabric, in readiness for the tightening of the thread. Fig. 6 is a view after the thread has been 55 partly tightened, the button-eye and the in-

terlocked loops being shown in section, as is also the fabric. Fig. 7 is a perspective view showing the finished knot, and in order to illustrate it more clearly the button-eye is shown in full lines but the button itself is in 60 dotted lines. Fig. 8 is a view showing the fabric in section and a button attached thereto by the finished knot, the final and long advance having been given to the fabric to position it for the attachment of the next 65 button, shown in dotted lines, when the needle again descends.

In carrying out in practical form my novel method the fabric is clamped between a stationary presser-foot and a yieldingly controlled work-support, which effects a proper securing of the fabric during the operation of attaching the button thereto while permitting a short initial advance of the fabric after the primary loop of thread has been passed 70 through the fabric and the eye of the button, a second and longer advance of the fabric being effected after the attachment of the button, to effect the completion of the feed, and then the work is unclamped before the operation is repeated with the next button to be attached. A hooked needle is employed to form the stitch, said needle moving in a single path, and the feed of the fabric is effected wholly independent of the needle. 75 After the secondary loop had been passed through the fabric and the primary loop such secondary loop is spread and temporarily held, and cast off from the needle, after which the loop is tipped over and placed 80 over the button close to the fabric, and then the thread is tightened by a suitable take-up, drawing taut the loops and completing the 85 attachment.

In the drawings the fabric is indicated at 95 F and 2 is a button having an eye or shank 3, the thread leading to the source of supply being indicated at 4.

Assuming the fabric to be held by suitable 100 means, as for instance, between a presser-foot and a work-support, the hooked needle is passed down through the eye of the button and the fabric, and the thread is carried around the needle, being caught by the hook thereof. The needle is now lifted, drawing 105 the primary loop 5 of the thread upwardly through the fabric and the eye of the button, as shown in Fig. 1, the button at this time being suitably supported, as for instance in the end of a raceway, with its eye 3 substan- 110

tially horizontal, a suitable hook-closer preventing accidental displacement of the loop from the needle. The fabric is now given a short initial advance or feed movement while 5 the needle is above the fabric and at rest, and the button is also moved forward, to move the button-eye clear of or beyond the path of the needle, and the needle is then moved downwardly away from the hook-closer, throwing off the primary loop 5, as in Fig. 2, while the needle descends through such loop and the fabric to its lowest point. Again the thread is carried around the needle and is caught by its hook, and the needle 10 then rises, drawing the secondary loop 6, up through the fabric and through the primary loop 5, as in Fig. 3, but outside of the button-eye, the loop 6 being held on the needle by the hook-closer, the primary and secondary loops now being interlocked. At this time 15 the button is released from its support, preferably by withdrawal of the support therefrom, so that the button drops down toward the fabric, as in Fig. 3. A loop-spreader is now moved bodily in a curved path above 20 the button, and the point of the spreader enters the secondary loop, the needle descending slightly to uncover the hook and release the loop, continued movement of the 25 spreader casting off the loop from the needle and spreading such loop, as shown in Fig. 4 in the shape of a triangle.

When the loop 6 is fully spread it is temporarily held while the bodily movement of 30 the spreader is completed, and the spreader is tipped downward to overhang the button, with its extremity below the bottom of the button and close to the button-eye 3, the secondary loop then being shed from the 35 spreader and placed over the button, as shown in Fig. 5. The slack of the thread is now taken up by the take-up, pulling the loops 5 and 6 taut around the eye of the button, as in Fig. 7, and the final long feed movement of the fabric is effected to position such 40 fabric for the attachment thereto of the next button, as shown in Fig. 8, the needle 10 being shown in readiness to descend through the eye of the next button to be attached, 45 indicated by dotted lines. The cycle of operations is now completed, and the fabric is unclamped and remains unclamped until just before the downward movement of the needle through the eye of the button next to 50 be attached.

When the thread is taken up after the secondary loop has been placed over and around the button any slack of the primary loop 5 is taken up, so that the primary and secondary 55 loops are drawn tightly together and the button-eye is pulled up against the fabric, as in Fig. 7, the button-eye being left substantially at right angles to the line of feed of the fabric.

60 Each button is firmly attached to the fab-

ric by interlocking loops, wholly independent of the attachment of the next button, so that should the intervening portion of thread between two adjacent buttons be severed the attaching knot of either button will not 70 be interfered with.

The illustration of the parts in Fig. 6 shows the interlocked primary and secondary loops 5 and 6 as partly tightened, and it is to be understood that ordinarily the upright position of the button will not be assumed until the final tightening of the loops to form the flat knot shown in Fig. 7.

When the needle is drawing the secondary 75 loop of the thread up through the fabric and the primary loop the thread at the side leading to the supply is held so that as the needle rises there will be a shortening of the primary loop, from the length shown in Fig. 2 to that shown in Fig. 3.

80 As the spread secondary loop 6 is moved from the position shown in Fig. 4 to that shown in Fig. 5 the loop changes from the triangular to the oval shape, due to the fact that the sides of the spreader converge to the tip thereof, so that when the tip is depressed to place the secondary loop around the button close to the fabric the sides of the loop slide down the sides of the spreader and slacken as the loop is discharged.

85 Having fully described my invention, what I claim as new and desire to secure by Letters Patent is:—

1. The herein described method of attaching a button to a fabric, which consists in 100 moving a needle downwardly through the eye of the button and the fabric to thread the needle, and then moving the threaded needle carrying a loop of thread upwardly through the fabric and through the eye of said button, to draw up a primary loop of thread therethrough; then advancing the fabric while the needle is elevated and at rest and holding the primary loop; next releasing such loop from the needle while the latter descends clear of the button-eye but through the primary loop and the fabric; then carrying the thread for the secondary loop around the needle and giving the needle a second 110 upward movement, drawing up a secondary loop of the thread through the fabric and the primary loop; then spreading the secondary loop and casting it off from the needle, and moving the spread loop bodily into position above the button; then shedding the spread 115 secondary loop and placing it over the button close to the fabric; and finally pulling the secondary loop taut around the eye of the button and the primary loop.

120 2. The herein described method of attaching a button to a fabric, which consists in 125 clamping the fabric with a suitable clamp and holding the button with its eye in the needle-path and moving the needle downward through the eye and the fabric; carry-

ing the thread about the lowered needle and moving the latter upward, drawing a primary loop of the thread through the fabric and the eye of said button; advancing the 5 fabric while the needle is elevated and at rest above it; next releasing the primary loop from the needle while the latter descends clear of the button-eye but through the primary loop and the fabric; carrying 10 the thread for the secondary loop around the needle; moving the needle upward and drawing the secondary loop through the fabric and the primary loop and releasing the button; next spreading and holding the 15 secondary loop and casting it off from the needle; temporarily holding the loop spread and moving it bodily into position above the said button; tipping and releasing the spread loop and placing it over the button close to the fabric; and finally pulling the 20 secondary loop taut around the button-eye and the primary loop.

3. The herein described method of attaching a series of buttons to a fabric, which 25 consists in clamping the fabric with a suitable clamp, then moving a needle downward through the fabric and the eye of the button, carrying the thread about the lowered needle

and moving the needle upward, drawing up a primary loop of the thread through the fabric and the eye; then giving a short initial advance to the fabric while the needle is elevated above it and at rest, and then moving the needle downward, casting off the primary loop, and continuing such movement 30 of the needle through such loop and the fabric; forming a secondary loop of the thread upon the needle, moving the latter upward, and drawing the secondary loop up through the fabric and the primary loop; spreading 35 and casting off the secondary loop from the needle and placing such loop over the button close to the fabric; tightening the secondary loop around the eye of the button, and finally giving a second and longer advance 40 to the fabric while the needle is elevated above it, to position the fabric for the attachment of the next button when the needle again descends.

In testimony whereof, I have signed my 50 name to this specification, in the presence of two subscribing witnesses.

BERNARD T. LEVEQUE.
